(57) **CLAIM**

The ornamental design for a multi-sensor interactive patient care pod, as shown and described.

DESCRIPTION

FIG. 1 is a front isometric perspective view of a multi-sensor interactive patient care pod in a closed orientation;

FIG. 2 is a top plan view thereof;

FIG. 3 is a front elevation view thereof;

FIG. 4 is a left side elevation view thereof;

FIG. 5 is a rear elevation view thereof;

FIG. 6 is a right side elevation view thereof;

FIG. 7 is a top view of the multi-sensor interactive patient care pod in an open orientation;

FIG. 8 is a front elevation view thereof;

FIG. 9 is a left side elevation view thereof;

FIG. 10 is a rear elevation view thereof; and,

FIG. 11 is a right side elevation view thereof.

The broken lines illustrate portions of the multi-sensor interactive patient care pod that form no part of the claimed design.
